(57) **CLAIM**

The ornamental design for a supplying port member for toner pack, as shown and described.

DESCRIPTION

FIG. 1 is a front view of a supplying port member for toner pack showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view thereof; and,

FIG. 8 is an enlarged view of the encircled portion in FIG.

7.

The dot-dash-dot broken line denotes the boundary of the enlarged detail view and forms no part of the claimed design. The dashed broken lines in the drawings illustrate portions of the supplying port member for toner pack which form no part of the claimed design.
